BURNER

Henry Lange, Quincy, Ill., assignor to The Quincy Stove Manufacturing Company, Quincy, Ill., a corporation of Illinois

Application December 24, 1934, Serial No. 758,912

16 Claims. (Cl. 158—99)

This invention relates in general to a burner for fluid or gaseous fuels and has more particular reference to a reversible burner for a gas stove.

An important object of the invention is in the provision of a burner of this kind consisting of a single casting which may be used in either a right or a left position.

A further object of the invention is in the provision of a double air adjustment for a gas burner casting of this kind.

A still further object of the invention is in the provision of a common support for an additional burner in either one of the two positions for which the burner casting is adapted.

In the accompanying drawing illustrating a preferred embodiment of the invention,

Fig. 1 is a plan view of a right and left burner arrangement for a gas burner;

Fig. 2 is a section taken on the line 2—2 of Fig. 1;

Fig. 3 is a side elevation of one of the burner castings;

Fig. 4 is a cross section taken on the line 4—4 of Fig. 3;

Fig. 5 is a cross section taken on the line 5—5 of Fig. 3;

Fig. 6 is a longitudinal section taken on the line 6—6 of Fig. 4; and

Figs. 7 and 8 are end views of the burner only in left and right positions respectively.

In locating the burners in a gas range it is customary to provide front and rear burners, generally in alignment with each other but separately controlled from the front of the stove or burner. This requires separate fuel supply pipes leading to the front of the range where the controlling valves are located, and when four or more burners are used it is customary to locate the fuel supply pipes together so that both a right and left fitting are required. This necessitates two different patterns, castings and parts for the burners, thereby increasing the expense, investment and the number of parts required to keep a stock of repairs on hand, and increases the errors in supplying repair parts.

The present invention provides a reversible burner casting which has counter part burner hole locaters on opposite sides of the burner, a common burner support intermediate the ends, and a double air supply adjuster at the inlet end of the casting so that a single burner casting may be utilized for both right and left burners.

Referring now more particularly to the drawing, a support for a gas burner is represented

as a marginal plate 10 having an offset inner rim 11 which normally supports an open framework or grill (not shown) below which the gas burners are placed. A burner of this kind must be supported a short distance below the top of the plate 10 in order to obtain the most efficient results in heating, but if the burner is located too low it will not allow sufficient space for a burner tray 12 below the burners. In the present invention a shallow reversible burner casting 13 is provided having an inlet 14 at one end, and a burner portion 15 near the other end connected by a straight tubular portion 16, and a tubular portion 17 at an angle thereto. Extending from the burner end is a projection 18 having an end slot 19 therein which is adapted to rest upon the lower ledge 20 of a bracket 21 and to be secured thereto by a fastening screw 22. The upper edge of the bracket 21 is removably supported in the rim 11 by projections 23 inserted in spaced openings thereof.

The other end of each burner casting 13 is supported at the inlet 14 by means of an opening 25 into which a stem 26 extends. This stem 26 is supported in horizontal position by the lower angled tube 27 of a burner valve 28, the valve being connected into and supported by a fuel supply pipe 29 which extends to the front of the burner under the margin of the top plate 10. Extending to the front of a depending flange 30 from each valve 28 is a valve stem 31 and an operating handle 32. A guard plate 33 with slots 34 in its upper edge extends from below the valves 28, the valve stems 31 registering with the slots 34 thereof for covering and protecting the valves and making a neat appearance at the front of the burner.

The opposite faces of each burner portion 15 are formed with outer rows of small bosses 35 and inner rows of similar bosses 36 preferably arranged in circles and with an opening 37 extending through the burner. Depending upon whether a right or left burner is desired, one of the sides of the burner portion 15 is provided with perforations 38 in the bosses 36 inclined inwardly toward the axis thereof and with perforations 39 in the bosses 35 inclined outwardly from the axis thereof, both series of openings connecting with the interior tubular space 40 which extends through the hollow stem portions 17 and 16 to the inlet end of the casting.

In the inlet 14 is a passage 41 extending from top to bottom and somewhat segmental in cross section, the top and bottom being covered by segmental plates 42 and 43 each secured in place 55.

near its axis by an adjustable fastening screw 44 so that either of these plates may be readily adjusted from the bottom of the casting when it is in position by simply loosening the screw 44 and adjusting the corresponding plate 42 or 43 to admit more or less air. The top plate is left closed to prevent dirt or other material from clogging the inlet.

It will be noted the faces of the burner portion 15 and of the inlet portion 14 are inclined toward each other, and each face is parallel to the opposite face of the other portion; and the straight tubular portion 16 is located at one side of the burner portion 15 and connected thereto by the inclined or angularly disposed portion 17. This makes it possible to avoid the extreme depth of head which would be necessary to maintain the upper burner face at the right distance below the stove top and also to connect the inlet 20 with the burner valves 28.

With this burner the straight tubular portions 16 are located on a line with the stems 26, and the connecting neck portion 17 is inclined upwardly to left or right position as shown by 25 Figs. 7 and 8. This inclination requires that the opposite faces of the burner portion be inclined to each other so that they will be parallel with the stove top 18 in both positions; and the supporting faces of the projection 18 are similarly, 30 but oppositely disposed to uphold the upper face of the burner in a level position parallel with the top.

At the inlet 14 end of the fitting the bottom face covered by plate 42 or 43 (depending upon 35 its left or right position) is parallel to the opposite upper face of the burner portion 15, and is maintained in a horizontal position. Air adjustment is made by varying the position of the bottom plate 42 or 43, the top plate remaining 40 closed, and preventing dirt from clogging the air inlet opening at that side.

By this construction, the neck portion 17 is inclined upwardly, maintaining a proper flow condition for the fuel, with the upper burner face in 45 level position, and the tapered passages in the ring-shaped burner portion 15 also help to equalize the pressure of the fuel mixture, as the portion 17 is connected to the side having the larger passage, resulting in a more uniform pressure from all of the burner ports.

Extending laterally from each burner casting 13 is a projection 50 having a supporting ledge 51 with a projection 52 thereon at each side of the projection 50. This ledge is for supporting 55 a short burner 53 preferably resembling the burner portions on the castings 13 and having short projecting legs 54 for engaging the uppermost ledge 51 of its burner castings 13 at the opposite sides of the projection 52 and thereby 60 holding this end of the burner 53 in place. The other end of the burner 53 is connected by a hollow stem 55 with an inlet 56 which may be similar to the inlet 14 but preferably has only one air controlling plate 42 and adjusting screw 65 44 for controlling the air inlet to the burner 53. It will be understood that these burners 53 are not reversible and therefore they do not require a double face or the double inlet construction described in connection with the burner castings 13.

With this construction a single burner casting 13 is provided for both right and left burners and the corresponding face of the burner only is provided with the fuel discharge openings 75 38 and 39, depending upon whether the burner

is turned for one face or the other; the connection of each burner casting is the same at the front and rear ends; and the supporting projections 50 being the same on both sides, will properly support the short burners 53 and hold them in proper position.

To mount the burner castings 13, the supporting bracket 20 may first be attached to the slotted extension 18 by the screw 22, the opening 25 of the inlet 14 is applied to the stem 26 and the 10 projections 23 of the supporting bracket 20 will then engage the openings 24 in the rim 11 of the plate 10, holding the burner firmly in place so that it will also support the burner 53 when applied to its projection 50.

I claim:

1. A reversible burner comprising a hollow member having means defining the location of burner holes on opposite sides thereof, the opposite sides being inclined with respect to each other and having openings through the said means on one side determining which side of the member is used, and having an integral hollow stem which extends at the right or left side of the member depending upon which side is uppermost; and means to support either uppermost face in a horizontal position.

2. A burner casting having a hollow ring with an integral supply stem extending laterally therefrom, the ring having bosses on opposite sides defining the positions for openings, and having openings on one side only for a right or left burner, the outer openings inclined outwardly and the inner openings inclined inwardly with respect to a central axis, the stem extending forwardly of the ring at opposite sides depending upon which side of the burner is uppermost.

3. An invertible fuel burner having oppositely inclined opposite faces, means on opposite faces defining the location of burner openings, a projection at one end by which the burner is supported in either position with the upper face in a horizontal plane, and an integral fuel supply stem extending opposite the projection and having an end fuel opening for engagement with a horizontally disposed supporting stem, the fuel supply stem extending forwardly on opposite sides of a median line depending upon which face is uppermost.

4. In a right or left burner, a hollow member 50 having a burner portion with opposite faces inclined with respect to each other and an integral hollow stem extending therefrom, means for loosely engaging the stem, and a support attachable to the end of the member opposite the stem to hold either of said faces in a horizontal position, the stem being disposed at either side of an intermediate center line depending upon which face is uppermost.

5. A right or left fuel burner comprising a hollow portion with oppositely inclined opposite burner faces, an integral hollow stem extending laterally therefrom having an end opening, a projection on said portion extending opposite the stem having its faces parallel with the opposite burner faces and having an open slot adapting the burner to be secured thereby in either of its two opposite positions, and the stem being located at one side or the other of an intermediate center line depending upon which face is uppermost.

6. A right or left fuel burner and a supporting frame, a fuel valve having a discharge stem at one side of the frame, a hollow burner casting having an integral pipe with an end opening to 75

fit over said stem supporting one end of the casting, a burner portion at the other end having opposite burner faces inclined with respect to each other and a projection with its faces similarly but oppositely inclined to those of the burner and an end slot, and a bracket engaging the frame and having means for securing the casting thereto by means of the slot with either burner face horizontally upward depending upon whether a right or left burner is desired, the location of the pipe to the right or left of a central position being determined by which face is uppermost.

7. A right or left burner having a burner portion with oppositely inclined opposite faces one of which is perforated and a support extending rearwardly having reversely inclined faces for holding the burner with either face horizontally uppermost, and an integral hollow tubular inlet 20 extending angularly forward and to that side of the burner depending upon whether a right or left offset is desired, and means for supporting the tubular inlet in either right or left burner position.

8. A right or left burner having a burner portion with opposite burner faces inclined with respect to each other, a hollow inlet portion located at one side of the burner and connected thereto by an angular portion, and means for 30 mounting the burner to bring either face in an uppermost horizontal position with the angular portion inclined upwardly at one side of the inlet portion.

9. A right or left burner comprising a casting 35 with opposite burner faces each located in a plane at an angle to an intermediate central plane, a hollow stem offset at one side of the burner and connected by a portion at an angle to the burner portion, and an air inlet at the end of the stem having opposite inlet faces also inclined and each face being parallel to the burner face at the opposite side so that the under side of the inlet will be parallel to the upper side of the burner face.

10. An invertible burner for right and left positions comprising a hollow casting with a burner portion having oppositely inclined opposite faces, a hollow stem and an inlet at the end opposite the burner with oppositely inclined air 50 inlet surfaces, each parallel with the opposite burner face, means for mounting the burner to hold either burner face in a horizontal upright position.

11. In an invertible right or left burner, a hollow casting having a ring burner portion with inclined opposite faces making an inner passage larger at one side, a hollow stem at one side of the burner portion, and an angular stem portion connecting the stem and the larger side of 55 the burner portion, whereby the casting is in-

clined upwardly with the hollow stem as an axis by the angular portion to bring one face of the burner portion in level horizontal position, and the tapered section of the burner producing a uniform pressure in the burner ports.

12. A structure in accordance with claim 8 in which one of the burner faces is provided with fuel holes inclined outwardly at the outside and inwardly at the inside of the face, and the burner faces are slightly inclined with respect to each other to direct the fuel from opposite faces at the same upward angles depending upon which face is used.

13. A structure in accordance with claim 9 in which the air openings terminate at opposite faces 15 of the inlet which are slightly inclined to each other and for each of which there is a closing plate and means for adjustably securing the plate in position to uncover more or less of the opening.

14. A right or left burner having a portion with opposite burner faces of which one is perforated and a rear extension for supporting it in either burner position, a hollow integral tubular inlet 20 extending forward at one side of the burner depending upon which face is used, and a burner supporting arm extending laterally from the tubular inlet and having similar supporting ledges on opposite sides to provide the same support independent of whether a right or left burner is used.

15. A right or left burner having a portion with opposite burner faces either of which is perforated and means at the rear for supporting it in either burner position, a hollow integral tubular inlet 35 extending forwardly at one side of the burner center line depending upon which burner face is used which center line passes through said supporting means, and an arm extending from the tubular inlet across said center line, and having similar opposite sides to support another burner 40 upon the same level as that of this burner.

16. In a gas stove, a frame for a plurality of front and rear burners, a plurality of fuel valves with supporting stems at the front of the frame, right or left burners each comprising a similar 45 casting with opposite burner faces of which one is perforated and rear supporting means and with an integral tubular inlet extending forwardly at one side of the front and rear center line of the burner face, an arm projecting inwardly from the 50 tubular inlet across the center line providing a similar support on both sides thereof, a plurality of short front burners each having a burner portion with rear projections to engage the support of one of said arms at its rear end and having a 55 tubular inlet at the front, the tubular inlets of the right, left and front burners being engaged and supported by the fuel valve stems at the front of the frame.

HENRY LANGE. 60
